UNITED STATES PATENT OFFICE.

EDWARD A. NIX AND JOHN J. DOWLING, OF NEW ORLEANS, LOUISIANA, ASSIGNEES
OF ONE-THIRD TO E. C. CALKINS, OF THE PARISH OF ORLEANS, LOUISIANA.

CAR-FRAME.

1,119,714.

Specification of Letters Patent. Patented Dec. 1, 1914.

Application filed April 12, 1913. Serial No. 760,791.

To all whom it may concern:

Be it known that we, EDWARD A. NIX and JOHN J. DOWLING, citizens of the United States, residing at New Orleans, in the 5 parish of Orleans and State of Louisiana, have invented certain new and useful Improvements in Car-Frames, of which the following is a specification.

This invention relates to car frames.

10 Doors of refrigerator and other cars are frequently left swinging with the result that they strike against some projection and are torn off, oftentimes, if not always, tearing loose the post to which the doors are swung. 15 It is at great trouble and expense that the doors and their posts are replaced. Sometimes when the doors alone are torn away from the posts the posts are loosened and it is expensive and sometimes impossible to 20 fasten the posts securely again. It is essential that the posts support the doors firmly, as it is necessary, especially in freight cars, to provide air tight joints. The doors are usually forced together with sufficient pressure to make the packing around them form air tight joints. If for any reason a door is so loose and it may be loose because of looseness of the posts, air tight 25 joints are not formed and refrigerator cars 30 under such conditions are useless for the purpose for which they are employed.

It is therefore one object of the present invention to provide supplemental posts for the hanging of the swinging doors and arrange them independent of the bracing beams and ordinary connecting posts of the framework so that in the event of loosening of the posts to which the doors are 35 swung the loosened posts may be readily replaced without interfering with the posts commonly employed to connect the upper and lower sills of the frame work.

Another object resides in the provision of means for hanging the doors of refrigerator 40 or other cars in such a manner that if the posts to which the doors are hinged or otherwise connected all become torn away from the frame the usual connecting posts between the upper and lower sills would not 45 be injured or otherwise disturbed as regards their permanent connection between the upper and lower sills or beams or other parts of the framework.

In the drawings: Figure 1 is a front 50 elevation of the invention. Fig. 2 is a ver-

tical transverse sectional view. Fig. 3 is a horizontal sectional view.

Referring now more particularly to the accompanying drawings the reference characters 5 and 6 indicate the upper and lower 60 beams or sills of the side of a car framework which are connected by the end posts 7 and 8 and by the intermediate posts 9 and 10, the character 11 indicating braces for the framework.

It has been the custom heretofore to hingedly connect the doors 12 and 13 to the posts 9 and 10 respectively. In the present instance the posts 9 and 10 are spaced apart a distance slightly greater than heretofore 70 and connecting them slightly below the top beam 5 of the framework is a strip 14 which forms the head of the door opening 15 and between this strip 14 and the beam 5 is preferably disposed a block 15.

Secured by means of bolts 16 or otherwise in the corners of the door opening 15 are metallic or other flanged sockets 17 adapted to receive the ends of the supplemental door posts 18 and 19, the sockets being open on 80 their outer sides to permit the ready insertion or withdrawal of these supplemental posts from the sockets. If the fastenings 16 for securing the sockets in place have their heads not countersunk in the sockets, the 85 ends of the supplemental posts 18 and 19 may be grooved as at 20 and in any event the outer edges at the ends of each supplemental post are preferably notched as at 21 so that the faces of the supplemental post with 90 which the edges of the doors abut may lie flush with the corresponding flange of the corresponding sockets.

From the foregoing it will be understood that in the construction described that the 95 braces and the posts, with the exception of the supplemental posts 18 and 19, and also the strip 14 are preferably connected rigidly one to another and rigidly connected to the upper and lower sills 5 and 6. The supplemental posts 18 and 19 are loosely mounted in the sockets. We retain these supplemental posts 18 and 19 normally in their sockets by means of sheathing 22 which is nailed over the frame of the car to form the 100 outside thereof. If the doors for any reason be pulled off of their mountings and the false posts are pulled loose or entirely out of their sockets, the car may be readily repaired by removing the sheathing 22 on the 105 110

outer side of the frame work and replacing the supplemental posts at comparatively little expense and with little loss of time and without in any way damaging the frame-work of the car. It is preferred that packing material 23 be placed between the fixed posts 9 and 10 and the removable or supplemental posts 18 and 19 for the purpose of providing air tight joints.

10 What is claimed is:

A frame work for cars including a door frame and its opening, sockets permanently mounted in the corners of the door opening of said frame, each socket at its front opening laterally outwardly and having a guide flange at its outer edge and a stop flange at its rear side, posts having their ends removably fitted in said sockets, and guided into the latter by said guide flange and limited in 15 inward movement by said stop flange, where-

by the opposite ends of the posts may be fitted in coöperating sockets simultaneously or simultaneously moved outwardly laterally of the car from the coöperating sockets and sheathing secured to the frame work of 25 the car and projecting inwardly beyond the edges of the door opening, in the path of movement of said posts for normally retaining the latter in their sockets.

In testimony whereof we have affixed our 30 signatures in presence of two witnesses.
